UNITED STATES PATENT OFFICE.

HENRY M. WILLIAMS, OF FORT WAYNE, INDIANA, ASSIGNOR OF ONE-FOURTH TO FRANZ BURGER, OF FORT WAYNE, INDIANA.

MIRROR DROP-CURTAIN.

SPECIFICATION forming part of Letters Patent No. 722,342, dated March 10, 1903.

Application filed February 25, 1901. Serial No. 48,805. (No model.)

To all whom it may concern:

Be it known that I, HENRY M. WILLIAMS, a citizen of the United States, residing at Fort Wayne, Allen county, State of Indiana, have 5 invented certain new and useful Improvements in Mirror Drop-Curtains, of which the following is a specification.

My invention relates to drop-curtains for theaters and the like, and has for its object 10 to provide a simple, cheap, and effective drop-curtain which shall be fireproof and fire-protecting and which shall also have a reflecting or mirror-like face; and to this end my invention consists in the various features of construction, substantially as hereinafter more particularly pointed out.

Referring to the accompanying drawings, wherein I have illustrated an embodiment of my invention sufficient to enable those skilled 20 in the art to understand the same, Figure 1 is a back view of the curtain, and Fig. 2 is an end elevation.

It is well known that metal, while of itself being fireproof, is more fire-resisting if it 25 is provided with a smooth or polished face, and I take advantage of this fact and make the curtain of metal having a polished surface, and this surface not only has the function referred to, but also performs the function 30 of a reflector, making a mirror-like surface, thereby adding to its practical function a pleasing effect.

With this general statement I will now describe the embodiment of the invention shown 35 in the drawings, wherein—

A and B represent two hangers, one at each side, which may be of any suitable material, but for the purpose of lightness are shown as made up of a skeleton framework, and these 40 hangers furnish bearings for two horizontal rollers C and D. The hangers are further braced in any suitable way, as by the rods E and F, making a light but sufficiently rigid frame, to which are attached any suitable 45 means for raising and lowering the same—as, for instance, the screw-eyes O—to which the ordinary ropes or other lifting device may be attached, as indicated.

Mounted on the frame and supported on 50 the horizontal rollers C and D is the curtain G, which, as above indicated, is preferably

of metal, having its surfaces polished. This curtain may be secured upon the rollers in any suitable way; but in order to provide for expansion of the metal I show adjustable 55 means for holding the curtain in place and at the same time for keeping it taut and smooth regardless of changes in length due to expansion. Thus the ends of the curtain are furnished with a bar or rod H H, to which 60 the metal is secured, and to the bars or rods in the present instance are secured the screws J and screw-hooks K, and interposed between these are suitable take-up devices, shown in the present instance as spiral springs L and 65 turnbuckles M, for adjusting the same.

In order to cheapen the cost of a wide plate of metal and to aid in the manufacture of the curtain, I construct it of a number of strips or widths of metal g g', &c., and these strips 70 have their edges abutting in close contact with each other and are secured together in any suitable manner, and I have shown their inner edges covered with strips h h', of any suitable material, attached to the adjacent 75 widths, and these may be of fabric cemented thereon or any other material which will properly hold the adjacent edges together. In the present instance I have shown each width of metal as having two spring-tension 80 devices connected therewith in order to furnish an even tension over all parts of the curtain; but more or less tension devices may be used.

With this construction I am enabled to provide 85 an effective fireproof curtain, which is also fire-resisting in that its surfaces are polished, and the polished surface also acts as a mirror or reflector, adding to the appearance of the curtain, as well as to its utility for the 90 purposes intended.

What I claim is—

1. A theater-curtain comprising a frame supporting a sheet of metal which presents upon its outer face a polished mirror-like surface, substantially as described. 95

2. A theater-curtain comprising a frame supporting a number of sheets of metal placed adjacent to each other, and means for adjustably holding the sheets in position on the 100 frame, substantially as described.

3. A theater-curtain comprising a movable

frame consisting of hangers and rollers supported in said hangers and a metallic curtain supported on the rollers and means for adjustably securing the curtain on the rollers, 5 substantially as described.

4. A theater-curtain comprising a frame having top and bottom rollers, a metallic curtain mounted on the rollers and spring-tension devices connecting the ends of the curtain, substantially as described.

5. In a drop-curtain, the combination with the frame having rollers, of a curtain com-

prising a number of sheets of metal mounted on the rollers, spring-tension devices between the ends of the rollers and adjusting devices 15 connected with the springs, substantially as described.

In testimony whereof I have signed my name to this specification in the presence of two subscribing witnesses.

HENRY M. WILLIAMS.
